United States Patent

Des. 241,480

Patented Sept. 14, 1976

241,480

MATERIAL HANDLING BOX

Robert L. Silver and Bert R. Eisenhut, Racine, Wis.,
assignors to The Triple E Corporation, Racine, Wis.

Filed Mar. 21, 1975, Ser. No. 560,809

Term of patent 14 years

Int. Cl. D3—99

U.S. Cl. D87—1 R

FIG. 1

FIG. 2

FIG.3

FIG.7

FIG.4

FIG.5

FIG.6

FIG. 1 is a perspective view of a material handling box embodying our new design;

FIG. 2 is another perspective view thereof and taken generally above and at one end of the box;

FIG. 3 is a top plan view thereof, on a reduced scale;

FIG. 4 is a side elevational view thereof, the opposite side being the same in appearance;

FIG. 5 is an end elevational view thereof, the opposite side being the same in appearance;

FIG. 6 is a bottom view thereof; and

FIG. 7 is a sectional view taken along the line 7-7 in FIG. 3.

We claim:

The ornamental design for a material handling box, substantially as shown and described.
